Harry Q. Schroeder
ATTORNEY

UNITED STATES PATENT OFFICE

GEORGE BROWN, OF OAKLAND, CALIFORNIA

WRENCH

Application filed January 20, 1930. Serial No. 421,993.

The invention forming the subject matter of this application relates to expansion or bushing wrenches.

When pipes are secured in place, usually 5 a pipe wrench or the like is employed for gripping the outer periphery of one end of the pipe, and for turning the same in the desired direction thereby to threadedly secure the pipe in position. When the pipe 10 is positioned within a wall and the end thereof protrudes beyond the surface of the wall but a short distance or is rendered entirely inaccessible then it is impossible to grip the end of the pipe by means of a pipe 15 wrench, or the like. In such instances the plumber uses an extension, such as a nipple, threaded on the end of the pipe and protruding beyond the wall surface to a sufficient distance to allow the gripping thereof 20 by the usual wrench, thus the pipe is manipulated through an extension temporarily attached to the end thereof.

The primary object of the invention is the 25 provision of a wrench adapted to extend within a wall or other covering surface and to frictionally engage the inside periphery of the end of a pipe disposed behind said surface, thereby allowing the gripping and turning of the pipe by a tool disposed beyond the end of the pipe.

Another object of the invention is the provision of a wrench the gripping members or jaws of which are capable of frictional engagement with the inner periphery of the 35 end of a pipe; said jaws are brought into said frictional engagement by being moved apart from each other on account of the usual manipulation of the handles of the wrench; the insertion of the jaws into the 40 end of any tubular member is rendered possible by the extension of the jaws beyond the sides of the handles of the wrench; the relative position of the handles being adjustable so as to vary the spacing between 45 the gripping members or jaws, whereby the use of the wrench in connection with pipes of different diameters is greatly facilitated.

Other objects of the invention are to provide a device of the character described that 50 will be superior in point of simplicity, in-

expensiveness of construction, positiveness of operation, and facility and convenience in use and general efficiency.

In this specification and the annexed drawings the invention is illustrated in the form considered to be the best, but it is to be understood that the invention is not limited to such form because it may be embodied in other forms; and it is also to be understood that in and by the claims following the description it is desired to cover the invention in whatsoever form it may be embodied.

The invention is clearly illustrated in the accompanying drawings, wherein:

Figure 1 is a perspective view of my wrench.

Figure 2 is a side elevation of the wrench showing the handles in disengaged position for the purpose of adjustment, and

Figure 3 is a side elevation of the wrench, showing the same in engagement with the inner periphery of a pipe.

Referring to the accompanying drawings wherein similar reference characters designate similar parts throughout, the various figures described above adequately illustrate my invention and the following detailed description is commensurate with the above mentioned drawings in enabling an artisan to construct and assemble the constituent parts of the same.

In carrying out my invention I make use of handles 6 and 7, one end of each handle is bent substantially at right angles to the longitudinal axes of the handles. The end of the handle 6 is bent in the direction of the handle 7, forming an arm 8; the end of the handle 7 is bent away from the handle 6 and substantially in parallelism with the arm 8, so as to form an upwardly extending arm 9, as illustrated in the drawings. The arm 9 is shorter than the arm 8 so that the upper ends of the arms are in alignment with each other, when the handles are in operative relation to each other.

On the free ends of the arms are formed transverse, gripping members 11, extending in parallelism with each other. The gripping members are of semicylindrical shape,

the flat sides thereof being opposite each other, so that when the gripping members are brought toward each other they form a cylinder. The outer curved surfaces of the gripping members 11 conform to the shape of the inner periphery of a tubular material, such as a pipe 12. The ends of the cylindrical sides of the gripping members are serrated as at 13, so as to form axially disposed teeth thereat. When the arms are moved away from each other to a proper distance the said serrated ends firmly grip the inner periphery of the pipe 12, allowing the moving or turning of the pipe 12, by the proper manipulation of the handles 6 and 7.

The operative connection between the handles 6 and 7 is established by means of teeth 14 on the upper edge of the handle 6 and by a sector 16 formed on the lower edge of the handle 7. The teeth of the sector 16 are in coacting relation with the teeth 14. In order to hold the handles 6 and 7 in coacting relation, with freedom of adjustment, a sleeve 17 is provided, in the upper portion of which is a pivot 18 for rotatably supporting the handle 7 at an intermediate point thereof. The sleeve 17 is slidable on the arm 6, in a manner to be presently set forth.

The sleeve 17 is made of such a length as to overhang below the handle 6 when the sector 16 is in engagement with the teeth 14. In order to grip the pipe 12, the gripping members 11 are inserted into the pipe 12, which insertion allows the gripping of the end of the pipe with freedom of the manipulation of the handles 6 and 7 beyond the end of the pipe 12, outside of the wall or other covering surface within which the pipe is positioned. The free end of the handle 7 is then pressed toward the free end of the handle 6, causing a pivotal movement of the handle 7 around the pivot 18 thereof. The aforesaid pivotal movement results in the swinging of the arm 9 away from the arm 8, whereby the gripping member 11 thereon is moved away from the complementary gripping member on the end of the arm 8. The outer cylindrical peripheries of the gripping members 11 are thus forced into firm, frictional engagement with the inner periphery of the pipe 12 and are held in such gripping position while the handle 7 is forced toward the handle 6. Now by the manipulation of the handles 6 and 7 in the usual manner, as a wrench, the pipe may be turned or otherwise moved without the obstruction of the handle movement, and without injury to the inner or outer periphery of the end of the pipe 12. Such injury and difficulty of manipulation of the tool handles are attendant to the use of the tools heretofore employed in connection with pipes the ends of which are inaccessible.

In order to render the wrench adjustable to pipes of different inner diameters the toothed portion of the handle 6 is extended to a convenient length on the upper edge of the handle 6. The adjustment is accomplished by the raising of the upper handle 7 and the sleeve 17 therewith until the sector is out of engagement with the teeth 14, then the handle 7 and the sleeve 17 therewith is slid on the lower handle 6 until the gripping member 11 on the arm 9 assumes the required spaced position relative the other gripping member.

After the gripping members 11 are properly spaced, the sector 16 is allowed to drop so in engaging position with the teeth 14 opposite thereto. Now the gripping members 11 may be inserted into the pipe 12, and the pivotal movement of the handle 7 will force the serrated ends of said gripping members 11 in firm, frictional engagement with the inner periphery of the end of the pipe and may be held in such position by holding the ends of the handles 6 and 7 in the gripping wrench position.

It will be recognized that a particularly facile tool is provided for the handling of tubular articles, the ends of which articles are inaccessible either on account of their closeness to an obstructing surface, such as a wall, or on account of being disposed behind such obstruction; furthermore the wrench heretofore described is adjustable to be used in pipes of different sizes; the wrench does not require any extension, careful supporting, or the insertion of the handles thereof into the wall or the like; the wrench combines positiveness of operation with a ruggedness of construction especially adapting it for its use. When the teeth of the sector 16 are dropped into engagement with the teeth 14 of the handle 6, the handles are locked thereby to each other against longitudinal movement relatively to each other, and during the pivotal movement of the handle 7 the fixed leverage is gained by the interlocking of the sector 16 and the teeth 14.

Having thus described my invention what I now claim as novel and desire to secure by Letters Patents is:

1. A wrench comprising a yoke, a lever pivoted in said yoke and having at one end thereof a transverse semi-cylindrical member provided with peripheral teeth, a sector gear on said lever eccentric to said pivot, a complementary gripping member slidable in said yoke and having rack teeth adapted for engagement with said sector gear, and a transverse semi-cylindrical member provided with peripheral teeth and adapted to engage the inner periphery of an object.

2. A wrench comprising a pair of oppositely disposed cooperating semi-cylindrical

internal jaws transversely disposed and respectively integral with a pair of cooperating levers, one of said levers being pivotally mounted in a yoke and having a toothed sector eccentric to the pivot and integral to the undersurface of the lever, the upper surface of the other lever comprising a toothed rack adapted for engagement with the toothed sector, said other lever being slideable in said yoke and adapted to be engaged or disengaged from said toothed sector.

5 3. A wrench comprising a pair of oppositely disposed cooperating semi-cylindrical internal jaws transversely disposed and intermediately integral with perpendicular portions of a pair of cooperating levers, one of said levers being pivotally mounted in the upper end of a yoke and having formed on the under surface a toothed sector eccentric to said pivot, the other of said levers having formed in the top surface, a toothed rack adapted for engagement with said toothed sector, said other lever being slideable in said yoke.

10 4. In combination, a toothed rack, formed on the inner longitudinal edge of a right angle bar, a semi-cylindrical jaw projecting transversely from both sides adjacent to the end of the short leg thereof, said bar being slideably retained in a yoke, a toothed sector integral with a second right angle bar and disposed on the outer longitudinal edge, a semi-cylindrical jaw for projecting transversely from both sides adjacent to the end 15 of the short leg thereof and adapted to cooperate with said first named semi-cylindrical jaw to form an inside gripping chuck, said second right angle bar being pivoted eccentrically of said toothed sector toward said jaw and within said yoke.

20 5. In combination, a yoke, a right angle lever pivoted in said yoke, a second right angle lever slideable in said yoke, transverse inner periphery gripping jaws integral with the short arms of said levers, and engaging means cooperating between said levers whereby a closing movement of the long arms of said levers causes a substantially longitudinal outward movement of said second right angle lever relative to said yoke, said jaws projecting from both sides of said levers.

25 In testimony whereof I have affixed my signature.

GEORGE BROWN.
